REFRIGERATION CONTROL SYSTEM

Alwin B. Newton, Minneapolis, Minn., assignor to
Minneapolis-Honeywell Regulator Company,
Minneapolis, Minn., a corporation of Delaware

Application April 27, 1940, Serial No. 332,001

8 Claims. (Cl. 62—8)

This invention relates to a control system for a refrigerating apparatus having evaporator means and a valve responsive to the outlet temperature of the refrigerant for regulating the flow of refrigerant to the evaporator means to maintain a desired amount of liquid refrigerant in the evaporator means.

An object of this invention is to provide a novel and commercially practicable arrangement for regulating the amount of liquid refrigerant in an evaporator and to prevent reducing this amount of refrigerant below a predetermined minimum.

These objects are accomplished by producing a false temperature at the temperature sensitive element of the usual thermostatic expansion valve by introducing refrigerant towards or at the end of the evaporator or evaporators. This refrigerant upon evaporating creates a lower temperature at the sensitive element of the thermostatic expansion valve thereby acting to change the control point thereof. By taking this refrigerant from the downstream side of the expansion valve so that it has already been partially expanded, reasonable quantities thereof can be utilized. Also, by introducing this refrigerant at a distance from the sensitive element of the thermostatic expansion valve its effect is reduced whereby the quantity utilized may be further increased. This also prevents any liquid refrigerant from reaching the sensitive element. As a result, the quantity of refrigerant introduced is made large enough to enable its control by an ordinary valve which can be commercially produced in quantities by regular production methods.

Also, by introducing this refrigerant at a point removed from the end of the evaporator unit, this refrigerant can actually be used to produce part of the refrigeration effect and this refrigeration effect can be made to act as the minimum capacity of the unit whereby it can be nicely controlled by properly choosing the point at which the liquid is introduced into the evaporator.

A further object of this invention is to automatically control the introduction of this refrigerant into the evaporator in accordance with the condition of the medium being controlled by the evaporator means. For example, it may be controlled by the temperature or relative humidity of the space being controlled.

A further object of this invention is to apply the arrangement outlined above to a refrigerating apparatus having a plurality of evaporators arranged in parallel, a distributor for distributing

liquid refrigerant to the evaporators and a common outlet for the evaporators.

Other objects and advantages will become apparent to those skilled in the art upon reference to the accompanying specification, claims and drawing, in which is diagrammatically illustrated the preferred form of this invention.

Referring now to the drawing, an air conditioning chamber is designed at 10. Located in the

chamber 10 is a cooling means 11 in the form of an evaporator unit. The cooling means is divided into three parallelly arranged evaporators 12, 13, and 14 having a common outlet 15. A distributor 16 of conventional design distributes liquid refrigerant to the parallelly arranged evaporators 12, 13, and 14. Outside or return air or a combination thereof may be passed through the air conditioning chamber 10 and over the evaporator unit 11 to the space being controlled, all as is well known in the art.

Refrigerant is circulated through the evaporators 12, 13, and 14 by means of a refrigerating apparatus generally designated at 23. The refrigerating apparatus may comprise a compressor 24 operated by an electric motor 25. Compressed refrigerant is discharged from the compressor 24 through a high pressure line 26 into a condenser 27. Condensed refrigerant is collected in a receiver 28 and flows through a liquid line 29 to the distributor 16 under the control of an expansion valve 30 and a normally open valve 17. Evaporated refrigerant is withdrawn from the evaporators 12, 13, and 14 through the common outlet 15 and a suction line 31 by the compressor 24.

Power is supplied to the compressor motor 25 by means of line wires 33 and 34 leading from some source of power, not shown, and the operation of the compressor motor 25 and hence the compressor 24 is controlled by a combined suction pressure and head pressure responsive controller 35 which may be of the type shown and described in application Serial No. 196,447 filed by Albert L. Judson and Carl G. Kronmiller on March 17, 1938. The controller 35 is connected

by a pipe 36 to the suction line 31 and by a pipe 37 to the high pressure line 26 so that the controller is operated in accordance with changes in suction pressure and head pressure. When the suction pressure increases to a predetermined high value and the head pressure decreases to a predetermined low value the controller 35 completes a circuit from the line wire 33 through the controller 35, wire 38 and compressor motor 25 back to the other line wire 34 to place the compressor 24 in operation. The compressor 24 re-

mains in operation until either the suction pressure decreases to a predetermined low value or the head pressure increases to a predetermined high value at which time the motor circuit is broken to stop operation of the compressor. Accordingly the compressor motor 25 and hence the compressor 24 are operated to maintain the suction pressure within predetermined limits. In case the head pressure should become excessive operation of the compressor 24 is stopped.

The expansion valve 30 which regulates the flow of liquid refrigerant to the distributor 16 is of the conventional thermostatic type having a diaphragm chamber 40. One side of the diaphragm located in the diaphragm chamber 40 is connected by a pipe 41 to the common outlet 15 of the evaporators 12, 13 and 14 so that the expansion valve is operated in accordance with pressure conditions existing within the evaporators 12, 13 and 14. The other side of the diaphragm is connected through a capillary tube 42 to a bulb 43 charged with a volatile fluid and located on the suction line 31 so as to respond to the temperature of the superheated refrigerant as it leaves the evaporators 12, 13 and 14. Upon an increase in pressure in the evaporators 12, 13 and 14 the expansion valve 30 is moved towards a closed position and upon an increase in temperature of the superheated refrigerant at the common outlet the thermostatic expansion valve is moved towards an open position. The thermostatic expansion valve operates to maintain a desired amount of liquid refrigerant in the evaporators 12, 13 and 14 in the usual manner.

A pipe 45 connected between the expansion valve 30 and the valve 17 is utilized for supplying auxiliary liquid refrigerant to the evaporators 12, 13, and 14 for the purpose of artificially cooling the bulb 43 of the thermostatic expansion valve to change the amount of liquid refrigerant maintained in the evaporators 12, 13 and 14. This pipe 45 leads into a distributor 47 and the supply of this auxiliary liquid refrigerant to the distributor 47 is regulated by a valve 46. Pipes 48, 49 and 50 extend between the distributor 47 and the evaporators 12, 13 and 14, respectively. The pipes 48, 49 and 50 are shown connected into the evaporators 12, 13 and 14 at a point between the inlets and outlets of these evaporators.

When the valve 46 is opened, liquid refrigerant is supplied adjacent the outlet of the evaporators 12, 13 and 14 and this liquid refrigerant expands in the evaporators and thereby cools the superheated refrigerant flowing past the bulb 43 of the thermostatic expansion valve. When the bulb 43 of the thermostatic expansion valve is thus decreased in temperature the thermostatic expansion valve 30 is moved towards a closed position to decrease the supply of refrigerant to the evaporators 12, 13 and 14. Thus the amount of liquid refrigerant maintained in the evaporators 12, 13 and 14 is decreased, the amount of decrease varying with the amount of liquid refrigerant admitted to the evaporators 12, 13 and 14 by the valve 46. By gradually positioning the valve 46 the amount of liquid refrigerant maintained in the evaporators 12, 13 and 14 may therefore be gradually varied.

The valve 46 may be manually positioned or it may be positioned in accordance with the condition of the medium being cooled by the evaporators 12, 13 and 14, such as the temperature of the space being conditioned by the air conditioning unit. In this respect the valve 46 may be

operated by an air motor 52 which receives air under pressure through pipe 53, adjustable orifice 54 and pipe 55 from a source of air under pressure 56. A bleed line 57 controlled by a controller 58 responsive to the temperature of the air in the space may be utilized for bleeding air from the air motor 52. When the space temperature is high, say 85°, the controller 58 closes the bleed line 57 whereupon maximum air pressure is supplied to the air motor 52. Under these conditions the air motor 52 holds the valve 46 closed so that a maximum amount of liquid refrigerant is being maintained within the evaporators 12, 13, and 14. As the space temperature decreases below 85° the controller 58 allows the bleed line 57 to decrease the pressure in the air motor 52 which allows the valve 46 to move towards the open position. As a result liquid refrigerant flows through the valve 46, the distributor 47 and pipes 48, 49 and 50 to the evaporators 12, 13 and 14 to decrease the amount of liquid refrigerant maintained in the evaporators 12, 13 and 14. Thus it is seen that the amount of liquid refrigerant maintained in the evaporators 12, 13 and 14 may be varied in accordance with changes in space temperature.

Since the refrigerant supplied to the evaporators 12, 13 and 14 under the control of valve 46 is taken from the downstream side of the expansion valve 30, its effect in cooling the bulb 43 will be much less than if it were taken from the upstream side of the expansion valve 30. This permits the utilization of larger quantities of refrigerant for this purpose and, since the quantity is small in any event, makes it possible to control this refrigerant by a valve 46 which can be produced commercially in quantities. Also, the connection of the pipes 48, 49, and 50 to the evaporators 12, 13 and 14 at a point somewhat removed from their outlet ends and between their inlets and outlets permits this refrigerant to evaporate and become somewhat warmed up before it effects the bulb 43. This again increases the quantity of refrigerant that may be utilized for the purpose of artificially cooling bulb 43 thereby rendering the quantity used sufficiently large to permit the valve 46 being of a type readily produced in quantities. This arrangement also insures that this added refrigerant will be evaporated and not in a liquid form when it reaches the sensitive element.

With the apparatus as thus far described, the distributor 47 should have a resistance less than that of the distributor 16. At least it should be no greater. When the valve 46 is wide open by reason of lowered room temperature, and since the resistance of distributor 47 is less than that of 16, most of the refrigerant flow will go by way of distributor 47 and very little will go by way of distributor 16. In this manner, by properly relating the resistances of these distributors and by properly picking the points in evaporators 12, 13 and 14 at which the lines 48, 49 and 50 are connected thereto, the manufacturer of the equipment can insure that no less than a predetermined minimum quantity of refrigerant will be furnished to the evaporators.

If it be desired to control this minimum quantity of refrigerant even more accurately, the distributors 16 and 47 can be given the same resistance and the valve 17 may be automatically controlled from the thermostatic controller 58. For this purpose the valve 17 may be provided with an operating motor 18 connected into the line 53 by a pipe 19. Then when the space tem-

perature is high and the bleed line 57 closed off, the air pressure operating in motor 18 will hold valve 17 open. As the space temperature decreases and the bleed 57 opens, the valve 17 will gradually close as the valve 46 opens and when the valve 46 is completely open then the valve 17 will be completely closed. This will prevent all flow of refrigerant to the inlets of evaporators 12, 13 and 14 by way of distributor 16 and the sole supply of refrigerant to these evaporators will be by way of distributor 17. By properly picking the size of distributor 17 and the points at which pipes 48, 49 and 50 connect into the evaporators 12, 13 and 14, it will be possible to accurately determine the minimum capacity below which the evaporator will never be operated.

This same arrangement of course can be used where there is but a single evaporator in which case the distributors 16 and 47 would be eliminated and there would be but a single connection such as 48 to the single evaporator.

If it be desired to control the amount of liquid refrigerant maintained in the evaporators 12, 13 and 14 in accordance with space relative humidity instead of space temperature, the controller 58 would be made responsive to space relative humidity. Under these conditions the controller 58 responding to an increase in relative humidity would decrease the pressure in the air motor 52 to decrease the amount of liquid refrigerant maintained in the evaporators 12, 13 and 14. As a result the temperature of the evaporators 12, 13 and 14 decreases to increase the amount of latent heat removal thereby.

Instead of utilizing the air operated control system described above it is obvious that an electric control system or a self-contained control system could be utilized and still remain within the scope of this invention. Although for purposes of illustration one form of this invention has been disclosed, other forms thereof may become apparent to those skilled in the art upon reference to this disclosure and therefore this invention is to be limited only by the scope of the appended claims.

I claim as my invention:

1. In combination with a refrigerating apparatus having a plurality of evaporators arranged in parallel for evaporating refrigerant, a distributor for distributing liquid refrigerant to the evaporators, a common outlet for the evaporators and means for circulating refrigerant through the evaporators, a thermostatic expansion valve including thermostatic means responsive to the temperature of superheated refrigerant adjacent the common outlet for the evaporators for regulating the flow of liquid refrigerant to the evaporators through the distributor to maintain a desired amount of liquid refrigerant in the evaporators, and means for supplying liquid refrigerant from between the expansion valve and the distributor to the evaporators for cooling the thermostatic means to change the amount of liquid refrigerant maintained in the evaporators.

2. In combination with a refrigerating apparatus having a plurality of evaporators arranged in parallel for evaporating refrigerant, a distributor for distributing liquid refrigerant to the evaporators, a common outlet for the evaporators and means for circulating refrigerant through the evaporators, a thermostatic expansion valve including thermostatic means responsive to the temperature of superheated refrigerant adjacent the common outlet for the evaporators for regulating the flow of liquid refrigerant to the evaporators through the distributor to maintain a

desired amount of liquid refrigerant in the evaporators, conduit means for supplying liquid refrigerant from between the expansion valve and the distributor to the evaporators for cooling the thermostatic means to change the amount of liquid refrigerant maintained in the evaporators and valve means in said conduit means for varying the flow of liquid refrigerant through the conduit means to regulate the amount of liquid refrigerant maintained in the evaporators.

3. A refrigeration system including a refrigerating apparatus having evaporator means in which refrigerant is evaporated and means for circulating refrigerant through the evaporator means comprising, the combination with said refrigerating apparatus of, a valve in control of the flow of refrigerant to the evaporator means, a thermostatic device responsive to the temperature of superheated refrigerant adjacent the outlet of the evaporator means for operating said valve to thereby regulate the flow of refrigerant to the evaporator means, a conduit having one end connected between said valve and the evaporator means and its other end connected into the evaporator means between the inlet and outlet thereof whereby refrigerant may be supplied to a portion of said evaporator means to lower the temperature of said portion of the evaporator means and thereby reduce the temperature to which said thermostatic means responds, and valve means in said conduit for regulating the flow of refrigerant therethrough.

4. A refrigeration system including a refrigerating apparatus having evaporator means in which refrigerant is evaporated and means for circulating refrigerant through the evaporator means comprising, the combination with said refrigerating apparatus of, a valve in control of the flow of refrigerant to the evaporator means, a thermostatic device responsive to the temperature of superheated refrigerant adjacent the outlet of the evaporator means for operating said valve to thereby regulate the flow of refrigerant to the evaporator means, a conduit having one end connected between said valve and the evaporator means and its other end connected into the evaporator means between the inlet and outlet thereof whereby refrigerant may be supplied to a portion of said evaporator means to lower the temperature of said portion of the evaporator means and thereby reduce the temperature to which said thermostatic means responds, and valve means operable to simultaneously increase the flow of refrigerant through said conduit and decrease the flow of refrigerant to the inlet of said evaporator means.

5. A refrigeration system including a refrigerating apparatus having evaporator means in which refrigerant is evaporated and means for circulating refrigerant through the evaporator means comprising, the combination with said refrigerating apparatus of, a valve in control of the flow of refrigerant to the evaporator means, a thermostatic device responsive to the temperature of superheated refrigerant adjacent the outlet of the evaporator means for operating said valve to thereby regulate the flow of refrigerant to the evaporator means, a conduit having one end connected between said valve and the evaporator means and its other end connected into the evaporator means between the inlet and outlet thereof whereby refrigerant may be supplied to a portion of said evaporator means to lower the temperature of said portion of the evaporator means and thereby reduce the temperature to

which said thermostatic means responds, and valve means operable to simultaneously stop the flow of refrigerant to the inlet of said evaporator means and increase the flow through said conduit to a maximum, whereby the minimum capacity at which the evaporator means can be operated is accurately determined.

6. A refrigeration system including a refrigerating apparatus having evaporator means in which refrigerant is evaporated and means for circulating refrigerant through the evaporator means for cooling a space, comprising, the combination with said refrigerating apparatus of a valve in control of the flow of refrigerant to the evaporator means, a thermostatic device responsive to the temperature of superheated refrigerant adjacent the outlet of the evaporator means for operating said valve to thereby regulate the flow of refrigerant to the evaporator means, a conduit having one end connected between said valve and the evaporator means and its other end connected into the evaporator means between the inlet and outlet thereof whereby refrigerant may be supplied to a portion of said evaporator means to lower the temperature of said portion of the evaporator means and thereby reduce the temperature to which said thermostatic means responds, and means responsive to the temperature of the space in control of the flow of refrigerant through said conduit.

7. A refrigeration system including a refrigerating apparatus having evaporator means in which refrigerant is evaporated and means for circulating refrigerant through the evaporator means for cooling a space, comprising, the combination with said refrigerating apparatus of, a valve in control of the flow of refrigerant to the evaporator means, a thermostatic device responsive to the temperature of superheated refrigerant adjacent the outlet of the evaporator means

for operating said valve to thereby regulate the flow of refrigerant to the evaporator means, a conduit having one end connected between said valve and the evaporator means and its other end connected into the evaporator means between the inlet and outlet thereof whereby refrigerant may be supplied to a portion of said evaporator means to lower the temperature of said portion of the evaporator means and thereby reduce the temperature to which said thermostatic means responds, and valve means controlled by space temperature for simultaneously decreasing the flow of refrigerant to the inlet of said evaporator means and increasing the flow of refrigerant through said conduit.

8. In a refrigerating system, the combination of an evaporator having a plurality of conduits each having an inlet and an outlet, a refrigerant distributor connected to the inlet of each conduit, a single expansion valve for controlling flow of liquid refrigerant to the distributor, said single expansion valve including an element responsive to the temperature of the vaporized refrigerant discharged from the evaporator, means for withdrawing a restricted flow of liquid refrigerant from a portion of the refrigerating system containing liquid refrigerant at a pressure intermediate that of the supply and the refrigerant pressure existing in the evaporator, said portion being between said valve and the inlets of said conduits, and supplying said withdrawn refrigerant to at least one of said conduits at a point remote from the inlet thereof, valve means whereby the flow through said withdrawing means is modulately controlled, and means responsive to a condition brought about by evaporation of refrigerant in said evaporator controlling said last mentioned valve means.

ALWIN B. NEWTON.
